PROCESS FOR SWEETENING NAPHTHAS

Georges G. Lukk, Cameron H. Caesar, and Stephen Ilnyckyj, Westfield, N.J., assignors to Esso Research and Engineering Company, a corporation of Delaware

Application November 15, 1952, Serial No. 320,706

5 Claims. (Cl. 208—203)

The present invention is concerned with an improved sweetening process. The invention is more particularly concerned with the conversion of mercaptan compounds, particularly those mercaptan compounds which have heretofore been relatively difficult to remove from hydrocarbon fractions, especially from those fractions boiling in the motor fuel, kerosene, diesel oil and heating oil boiling ranges. In accordance with the present invention, a feed hydrocarbon oil characterized by containing mercaptan compounds is contacted with an oxygen-containing gas and a treating agent comprising activated carbon impregnated with a critical amount of caustic.

It is well known in the art to treat petroleum oils by various procedures in order to remove or convert objectionable compounds to less objectionable materials, as for example, it is known to treat petroleum fractions boiling in the motor fuel boiling range and in the general range below about 700° F. with various chemical reagents such as sodium or potassium hydroxide solutions. Also it is known that weakly acidic materials, such as mercaptans, are reactive to various degrees with basic materials. Thus, one method for the removal of mercaptans from hydrocarbon streams has been to treat the streams with a reagent which is insoluble in the hydrocarbon stream but which contains alkali type of material which reacts with mercaptans. Such treating reagents have normally been aqueous solutions. The reaction product is a basic salt of the mercaptan. Normally such salts exhibit some solubility in the aqueous phase, this solubility decreasing as the molecular weight or branching of the hydrocarbon structure of the mercaptan increases.

The art has generally been recognized in the treating of hydrocarbon streams with aqueous solutions such as strong or weak caustic in a continuous type process, that the equilibrium is generally unfavorable for mercaptan extraction. Therefore, caustic solutions when they are spent only to a small extent in mercaptide salts will not give any further reduction in mercaptan content despite the fact that these treating solutions have a large residual free-caustic content. The art has also recognized that the efficiency of the spent caustic can be partially or fully restored by regeneration of these solutions. The regeneration normally consists of removal of a part or all of the mercaptide salts by means of hydrolysis and vaporization or by oxidation.

One method is to employ steam regeneration for the revivification of caustic solution spent in mercaptan removal from hydrocarbon streams. The steam regeneration is normally carried out in a packed tower or a tower provided with bubble plates or pierced type tray plate design. The steam hydrolyzes the mercaptide salts to the corresponding mercaptans which are stripped out by the steam vapors and taken overhead. The regenerator also serves as a means of adjusting the gravity of the caustic solution, which has been shown to be critical. The regenerated caustic is withdrawn from the bottom

2

of the regeneration tower and reused in the extraction stage of the system wherein the caustic contacts the hydrocarbon stream through suitable mixing devices for further extraction of mercaptans by the same caustic.

5 It has also been suggested that a treating agent comprising carbon and caustic be utilized for the removal of mercaptan compounds from an oil by converting the mercaptan to corresponding relatively harmless mercaptides and adsorption of the latter on the carbon. It has 10 now been discovered that the mercaptides in the caustic-on-carbon system can be readily oxidized to disulfides. This increases greatly the amount of feed which can be sweetened by a batch of caustic impregnated activated carbon, provided that an oxidizing agent, e.g., oxygen 15 is dissolved in the feed. It has been further discovered that if a critical ratio of carbon to caustic is employed, unexpected desirable results are secured both with respect to the extent of conversion of mercaptans to disulfides and with respect to the catalyst life.

20 The process of the present invention may be more fully understood by reference to the drawing illustrating an embodiment of the same.

Referring specifically to the drawing, a light virgin naphtha feed oil boiling in the range from about 100° 25 F. to 300° F. is introduced into the system by means of line 1. The oil is passed through a sand filter 2 wherein any water is segregated from the oil and removed by means of line 3. The oil is removed from filter 2 by means of line 4 and mixed with an oxygen-containing 30 gas as for example air, which is introduced into the system by means of line 5. The oil is then passed alternately through reactors 7 and 8 wherein the same is contacted with activated carbon impregnated with caustic soda. The treating agent is prepared preferably by mixing water which is introduced into the system by means of line 9 with sodium hydroxide, preferably in a concentration of about 50° Bé, which is introduced into the system by means of line 10. The aqueous caustic is passed to a mixer 11 where in the same is mixed with activated 35 carbon which is introduced into the system by means of line 12. The finished catalyst is mixed in a slurry drum type mixer 13 with naphtha from line 15 and passed to the respective reactors 7 or 8 by means of line 14. Treated oil is removed from the reactors 7 and 8 by lines 40 16 and 17 respectively. The treated product is passed to a product storage zone 18 wherein the air is removed by means of line 19.

While the operation has been described wherein naphtha is percolated through a fixed bed of activated 50 carbon impregnated with caustic, it is to be understood that a fluidized bed or a slurry type operation may be utilized. In accordance with the present invention air or other oxygen-containing gas is introduced into the naphtha stream prior to percolating the feed through 55 the impregnated activated carbon in order to supply the oxygen required for the oxidation reaction in accordance with the following:

60 The process generally comprises the conversion of mercaptan compounds present in oils boiling below about 700° F. to corresponding disulfides using a catalyst comprising activated carbon impregnated with an alkali metal hydroxide, particularly sodium hydroxide. The catalyst 65 consists of carbon impregnated with an aqueous solution of an alkali metal hydroxide. The amount of this solution, should be 50% or less than the maximum amount that can be taken up by the carbon. The ratio of the hydroxide to water should be such, that a solution rather than a solid will result at the operating temperature. For 70

example, the weight of sodium hydroxide should not exceed the weight of the water. In the case of potassium hydroxide a higher concentration of KOH to water can be used. When employing a catalyst of these critical ratios, a high degree of conversion is secured and a high catalyst life.

The catalyst of the present invention may be prepared either by (1) direct mixing of the components or by (2) soaking the carbon in dilute caustic followed by removal of the excess water by drying. An application of the first method is illustrated in the attached drawing. Activated carbon and a solution of caustic in water are introduced simultaneously into a mechanical mixer, e.g. of the concrete mixing type. If the components are introduced separately the carbon is first added to the mixer followed by the caustic solution. The proportions of the three components are selected in accordance with the desired final catalyst composition. The optimum addition rates of the components (or of the caustic solution) will depend upon the efficiency of the mixing device. Mixing times of 10 to 15 minutes are adequate.

The alternative method of soaking and drying appears to be particularly suited for catalyst preparation or regeneration in situ.

The process of the present invention may be more fully understood by the following examples illustrating the same.

EXAMPLE 1

A number of operations were conducted wherein the treating agent comprised activated carbon impregnated with caustic; activated carbon alone and caustic alone. The results of these operations are shown in the following table:

Table I

INDIVIDUAL ACTION OF COMPONENTS OF CAUSTIC-ON-ACTIVATED-CARBON CATALYST

Feedstock—Naphtha of 100-250° F. Boiling range, 16 Cu No. Air to feed ratio—1/3.

Added Material	Parts by Weight		
	Catalyst	Carbon	NaOH Solution
Dry Carbon.....	4.1	4.1	0.9
NaOH.....	0.9	—	2.3
Water.....	2.3	0.6	—
Percent RSH Reduction			
Bbls./lb. Cat.:			
0.05.....	100	24	22
0.1.....	100	13	22
0.2.....	100	7	22
0.3.....	100	6	22

From the above it is apparent that unexpected results are secured utilizing activated carbon in conjunction with caustic and air.

EXAMPLE 2

A number of operations were conducted wherein catalysts prepared by different procedures were utilized. The results of these operations are given in the following table:

Table II

EFFECT OF METHOD OF CATALYST PREPARATION UPON SWEETENING WITH CAUSTIC ON ACTIVATED CARBON

20 Feedstock—Naphtha of 100° F. to 250° F. Boiling range, 15 Cu No. Catalysts—56% dry carbon, 12% NaOH, 32% water. Air to feed ratio—1/4. Feed rate—8 w.w. (catalyst)/hr.

Catalyst Preparation	Direct Mixing of Components		Soaking and Drying		
	Bbls. Feed/Lb. of Catalyst	Cu No. of Product	Converted S as equivalent percent of NaOH of Catalyst	Cu No. of Product	
30	1.....	Doctor Pass.	44	Doctor Pass.	44
	2.....	½.....	86	...do.....	88
	3.....	1.....	127	...do.....	131
	4.....	1.....	168	½.....	174
35	5.....	2.....	206	4.....	206
	6.....	2.....	244	6.....	232
	7.....	3.....	280	8.....	253

From the above it is apparent that while the soaked and dried catalyst exhibits a higher activity in the early part of the sweetening operation, the catalyst prepared by direct mixing shows superior activity maintenance.

EXAMPLE 3

A number of operations were conducted wherein the amount of air utilized was varied. The results of these operations are shown in the following table:

Table III

EFFECT OF AIR TO FEED RATIO ON SWEETENING WITH CAUSTIC ON ACTIVATED CARBON

Feedstock—Naphtha of 100° F. to 250° F. Boiling range, 15 Cu No. Catalysts—56% dry carbon, 12% NaOH, 32% water, prepared by mixing. Feed Rate—8 w.w. (catalyst)/hr.

Air to feed vol. ratio.....	1/3		1/1.5		1/0.7	
	Cu No. of product	Converted S as equivalent percent of NaOH of catalyst	Cu No. of product	Converted S as equivalent percent of NaOH of catalyst	Cu No. of product	Converted S as equivalent percent of NaOH of catalyst
2.....	Doctor Pass.	88	Doctor Pass.	88	Doctor Pass.	88
4.....	0.5.....	172	0.5.....	172	D.P.....	175
6.....	0.5.....	257	0.5.....	257	D.P.....	263

10.....	2.5.....	406	1.0.....	424	2.0.....	424
12.....	3.0.....	475	2.0.....	500	9.5.....	456

EXAMPLE 4

A number of operations were conducted wherein the ratio of carbon to caustic was varied. The results of these operations are given in the following table:

4. A process as defined by claim 1 wherein said oil is contacted with said catalyst in the presence of from 1 to 6 times the amount of oxygen theoretically required for the conversion of mercaptans into disulfides.

Table IV

EFFECT OF CATALYST COMPOSITION ON SWEETENING OF NAPHTHA WITH CAUSTIC ON ACTIVATED CARBON

[Variations of moisture content at C to NaOH ratio of 61:13 and of carbon content at NaOH to H₂O ratio of 13:26]

Feedstock—Naphtha 100° F. to 325° F.E.P., 16 Cu No.

Catalysts—Prepared by soaking and drying carbon, 20/100 mesh.

Feed rate—125 w.w. (of carbon)/hr.

Air to feed ratio—2/3.

Oper.	Catalyst composition (dry base/NaOH/H ₂ O)										
	1 35/8/56 ¹	2 44/9/47	3 56/12/32	4 61/13/26	5 68/14/18	6 71/15/14	7 73/16/11	8 77/17/6	9 80/17/3	10 40/20/40	11 52/16/32

¹ Carbon saturated with caustic solution.

From the above it is apparent that a catalyst which comprises 55 to 62 parts by weight of 20 to 100 mesh carbon, 11 to 14 parts by weight of alkali metal hydroxide and from 33 to 25 parts by weight of water is superior. With finer carbon of the same type better results are obtained if the concentration of the solution is increased.

What is claimed is:

1. A process for converting mercaptans contained in a hydrocarbon oil boiling in the motor fuel boiling range into disulfides which comprises contacting said oil in the presence of an oxygen-containing gas with a catalyst consisting essentially of 20 to 100 mesh activated carbon having an aqueous alkali metal hydroxide solution adsorbed thereon; said catalyst containing from 55 to 62 parts by weight of carbon, from 11 to 14 parts by weight of alkali metal hydroxide and from 25 to 33 parts by weight of water.

2. A process as defined by claim 1 wherein said alkali metal hydroxide is sodium hydroxide.

3. A process as defined by claim 1 wherein said oxygen-containing gas is air.

5. A process for the conversion of mercaptans in a naphtha into disulfides which comprises contacting said naphtha with from 1 to 6 times the amount of oxygen theoretically necessary for conversion of the mercaptans therein into disulfides and with a catalyst consisting essentially of from 55 to 62 parts by weight of 20 to 100 mesh activated carbon, 11 to 14 parts by weight of sodium hydroxide and 25 to 33 parts by weight of water.
